UNITED STATES PATENT OFFICE.

ANDREW C. ZWARICH, OF HOMESTEAD, PENNSYLVANIA.

SPRING DRIVE MECHANISM.

1,355,585.

Specification of Letters Patent. Patented Oct. 12, 1920.

Application filed December 20, 1919. Serial No. 346,353.

To all whom it may concern:

Be it known that I, ANDREW C. ZWARICH, a subject of the Government of Russia, residing at Homestead, in the county of Allegheny and State of Pennsylvania, have invented certain new and useful Improvements in Spring Drive Mechanisms, of which the following is a specification.

This invention relates to new and useful improvements in drive mechanisms particularly spring drive mechanisms adapted for use in connection with the operation of chronometers, or for any other purpose for which the mechanism is found applicable, and the invention has for its objects to provide a driving mechanism of the type set forth, in a manner as hereinafter referred to, which is comparatively simple in its construction and arrangement, strong, durable and efficient in its use, and inexpensive to manufacture.

To the accomplishment of these and such other objects as may hereinafter appear, the invention consists of the novel construction, combination and arrangement of parts herein specifically described and illustrated in the accompanying drawing wherein is shown an embodiment of the invention, but it is to be understood that the device shown is merely illustrative and that various changes in the form, proportion and minor details of construction may be resorted to, without departing from the principle or sacrificing any of the advantages of the invention, which come within the scope of the claim hereunto appended.

In the drawing forming a portion of this specification and wherein like numerals designate corresponding parts throughout the several views:

Figure 1 is a top plan view of a spring drive mechanism in accordance with this invention.

Fig. 2 is a sectional view of the device on line II—II, Fig. 1.

Fig. 3 is a sectional view on line III—III, Fig. 2.

Referring in detail to the drawing, the spring drive mechanism, in accordance with this invention, consists in part of the circular gear casing 1, comprising a bottom 2 and a vertically extending flange 3. The bottom 2, of the gear casing 1, is formed with a centrally disposed, upwardly extending cylindrical bearing 4, in which the vertical shaft 5 is rotatably mounted.

A pair of integrally formed gears 6 and 7 are mounted for rotation on the bearing 4 within the gear casing 1. The top gear 6 is of less diameter than the bottom gear 7. 60

Rotatably mounted on the shaft 5 and seated on top of the bearing 4 is the spring casing 8, in which a coil spring 9 is carried. One end of the spring 9 is connected, as at 10, to the shaft 5, while the other end thereof is connected, as at 11, to the spring casing 8. The spring casing 8 is further provided with a suitable cover plate 12.

A gear ring 13, having teeth formed on its inner periphery, is mounted on top of the flange 3, of the gear casing 1, and mounted on the gear ring 13 is a casing ring 14, which latter surrounds the spring casing 8, and is provided with the top plate 15.

The gear casing 1, gear ring 13, casing ring 14, and the top plate 15 are securely connected together by means of the bolts 16, as clearly shown in Fig. 2, of the drawing.

The upper end of the shaft 5 is suitably journaled, as at 17, in the top plate 15, and carries the operating gear 18 fixedly mounted thereon by means of the screw 19. A winding gear 20, provided with a hand-hold turning bar 21, is suitably journaled in the top plate 15 and meshes with the operating gear 18. 85

To prevent the return movement of the shaft 5 when the spring 9 thereof is wound, and to maintain the latter in the tensioned position, a catch 22 is provided which is pivotally connected, as at 23, to the top plate 15, and has a curved end 24 adapted to engage the teeth of the operating gear 18. A spring 25 is carried by the top plate 15, as at 26, which acts against the catch 22 to normally hold the latter in engagement with the teeth of the operating gear 18. 90

A pinion 27 is rotatably mounted on the shaft 28, which latter is fixed to the bottom of the spring casing 8 adjacent the outer edge thereof. The pinion 27 is positioned intermediate of the top gear 6 and the gear ring 13 and is in mesh with both. 100

A vertical shaft 29, suitably journaled in the casing of the mechanism in any desired manner, carries the pinion 30 at its lower end and the transmission gear 31 at its upper end, both of which are fixed to the shaft 29 to turn therewith. The pinion 30 meshes with the bottom gear 7 to drive the transmission gear 31 which connects to any appliance it may be desired to operate. 105 110

In practice the operation of the device is as follows: Turning the winding gear 20 in the clockwise direction it will turn the gear 18 and tensionally coil the spring 9 on the shaft 5. The action of the spring actuated catch 22 will hold the spring 9 in the tensioned position. The spring 9 now being tensioned around the shaft 5 and attached to the latter and to the spring casing 8, will cause the spring casing 8 to rotate on the shaft 5. Upon such rotation the pinion 27 will be rotated by its engagement with the stationary gear ring 13 and rotate the gear 6 with which the pinion 27 also meshes. The gear 7 being integral with gear 6 will also be rotated and cause the rotation of the pinion 30, shaft 29 and the transmission gear 31.

What I claim is:

A driving mechanism comprising a power transmitting spring, a casing connected therewith and revolved thereby, a gear casing having a stationary gear rack fixed thereto, a pinion carried by the spring casing and operated by said gear rack during the revolution of said spring casing, a gear mechanism driven by said pinion operatively connected with a transmission gear for driving the latter, and a shaft upon which is revolvably mounted said spring casing and gear mechanism, said shaft further constituting a winding element for said spring.

In testimony whereof I affix my signature.

ANDREW C. ZWARICH.
